UNITED STATES PATENT OFFICE.

JOHN L. CREVELING, OF NEW YORK, N.

TELEPHONE APPARATUS.

No. 920,277.

Specification of Letters Patent.

Patented May 4, 1908.

Application filed November 5, 1908. Serial No. 461,111

To all whom it may concern:

Be it known that I, JOHN L. CREVELING, a resident of New York, in the county and State of New York, have invented a certain 5 new and useful Improvement in Telephone Apparatus, as set forth in the annexed specification and drawing, forming a part thereof.

My invention pertains to that class of apparatus intended to be used in connection 10 with the ordinary receiver of a telephone and has for its principal object to render the sound impulses emitted by a single telephone receiver audible to both ears of an operator instead of one only as is usual.

It is a further object of my invention to 15 cut out extraneous disturbances which ordinarily tend to confuse or annoy a person using a single receiver leaving one ear open to the effect of such impulses.

20 It is a further object of my invention to provide a simple and efficient device for fulfilling the above functions which may be readily applied to the ordinary telephone receiver without defacing or altering the same 25 and which when applied will alter the effect of the usual receiver on a single ear in the least possible manner when the connection to the second ear is not used, and when the same is in use, alter the action of the ordinary 30 receiver upon the ear to which it is applied in the least possible manner.

Figure I. shows a side elevation and partial section of one type of my improved apparatus. Fig. II. shows a side elevation and partial 35 section of a modified form of the apparatus shown in Fig. I. Fig. III. shows an end elevation of one type of spring means of attaching my improved apparatus to the ordinary receiver. Fig. IV. shows a side elevation 40 of the device shown in Fig. III.

In Fig. I. (1) represents the body portion 45 of the ordinary telephone receiver, in this instance shown as the standard Bell type, provided with a threaded portion (2), dia-

phragm (3), and ear piece (4) having the aperture (5) normally intended to register with the opening of an operator's ear. (6) represents one ear piece of my improved apparatus shaped on one side to fit 50 closely the contour of the ear piece (4) and so shaped as to present at its other side substantially the same contour as the corresponding face of the ear piece (4). The ear piece (6) is provided with aperture (7) regis- 55 tering with the aperture (5) and communicating with the sound duct or passage (8)

which terminates in the opening of the metallic screw threaded bushing (9) adapted to receive the threaded nipple (10) in operative connection with a sound tube (11). The ear 60 piece (6) may be held in place upon the ear piece (4) by means of a spring ring (12) engaging a circumferential groove (13) and provided with fingers (14) adapted to spring over or grip the member (4).

(15) represents an ear piece provided with a central opening (16) adapted to register with the opening of the ear of an operator and communicating with the interior of the nipple (17), which is in operative communication with the sound tube (11). The nipple (17) may be provided with a branch opening (18) into which may be placed a ball (19) held therein as by the screw cap (20) in such manner that when the ear piece is in the position as shown in Fig. I. the ball will roll in the branch passage and in no way obstruct the passage through the nipple (17), while if the ear piece be inverted the ball (19) may roll down into the main passage of the nipple 80 (17) so as to close communication between the nipple and the opening (16) as shown for example in the corresponding ear piece illustrated in Fig. II.

The above description applies to the modification shown in Fig. II. save that the sound duct (21) is a tubular opening entirely within the ear piece (6) communicating with the aperture (7) and a portion of the inner surface of the ear piece (6) is shown as provided 90 with a felt or other yielding lining as illustrated at (22) and the ear piece (6) is shown as held in place upon the ear piece (4) by means of clips (23) carried by spring ring (24) as will hereinafter more plainly appear. 95 The ear piece (15) is the same as shown in Fig. I. and is in the inverted position described in reference to Fig. I.

In Figs. III. and IV. (23) represents the fingers adapted to hold the ear pieces together as shown in Fig. II. which are carried by the spring ring (24) adapted to hold said fingers in close contact upon the ear pieces when sprung over the same.

The practical operation of my improved 105 telephone apparatus is substantially as follows: The ear piece (6) is placed against the ear piece (4) as shown in Fig. I. and if desired may be held in place thereon as by means of spring ring (12) and fingers (14) as 110 indicated, then if the ear piece (6) be presented to one of the ears of an operator the

sound waves set up by the vibrations of the diaphragm (3) will be propagated through the apertures (5) and (7) so as to be audible to the ear to which the said receiver is presented. Waves will also be propagated through the duct (8), nipple (10), tube (11) and nipple (17) to the opening (16) of the ear piece (15) when held in the position shown in the drawing, in which position it may be applied to the other ear of an operator to cause the vibrations set up by the diaphragm (3) to be audible to that ear, and by proper construction of the ear piece it will be made serve to cut out extraneous sounds which would ordinarily tend to confuse an operator.

If for any reason the operator should not desire to place the ear piece (15) to the second ear but should just allow the same to drop and hang on the sound tube (11) it will then assume the inverted position shown in Fig. II, in which position the ball (19) will roll against the aperture of the nipple (17) in such manner as to close the same and prevent a waste of energy due to the sound waves being propagated through the tube (11) to the aperture (16) and thence dissipated without effect. As soon as this piece is picked up and placed to the ear the ball (19) will roll back into the position shown in Fig. I, and the sound waves will then cause an effect on the ear to which said ear piece is applied.

The above description of the operation of my device is applicable to the ear piece (6) indicated in Fig. II, which is identical with the ear piece (6) of Fig. I, with exception that the duct (21) is entirely within the piece (6) as may be preferable and the abutting surface of the ear piece (6) is covered with a felt or other suitable lining (22) which will serve to make a sound tight joint between the two pieces. In this figure the two ear pieces (6) and (4) are shown as held in operative relation to each other by fingers (23) which are held in place upon the ear piece as by means of the elastic ring (24) which carries the said fingers. The construction of this type of spring ring may be readily understood with reference to Figs. III. and IV. and it will be obvious that by properly opening ring (24) the same may be sprung upon the ear pieces (4) and (6) in such manner as to hold them together.

I do not wish in any way to limit myself to any exact device or construction shown in the accompanying drawing which is a mere representation of particular types of apparatus embodying my invention and in which considerable alterations may be made without departing from the spirit of my invention.

I claim—

1. The combination with a receiver having an ear piece, of an ear piece adapted to be placed against said receiver ear piece and against the ear of an operator, an aperture

for the transmission of sound waves therethrough, said ear piece being so shaped as to form a substantially close joint between itself and the receiver ear piece and provided with a sound duct in communication with the above mentioned aperture, said duct being in operative connection with a sound tube and a second ear piece in operative connection with said sound tube.

2. The combination with a receiver having an ear piece provided with an indentation, of an ear piece provided with an extension adapted to substantially fill said indentation, an aperture in said ear piece adapted to register with the ear of an operator and having in communication therewith a sound duct operatively connected with a sound tube provided at its other extremity with an ear piece communicating therewith.

3. The combination with a telephone receiver provided with an ear piece having a surface adapted to be placed against the ear of an operator, of an ear piece so shaped as to substantially abut a greater portion of said surface and present on its opposite face a surface adapted to be placed against the ear of an operator, an aperture in said ear piece adapted to transmit sound waves therethrough, a by-pass in communication therewith and operatively connected to a sound tube provided with an ear piece adapted to be held against another ear of an operator.

4. The combination with a telephone receiver having a surface adapted to be placed against the ear of an operator, of a member adapted to be placed against said surface and make an approximately close contact therewith on one side and present upon the other side a surface adapted to be placed against the ear, an aperture in said member for transmission of sound waves therethrough, an ear piece and means operatively connecting said ear piece with said aperture.

5. The combination with a receiver having an ear piece, a member adapted to be placed between said ear piece and the ear of a user and transmit sound therethrough, a second ear piece in operative connection therewith and adapted to convey sound impulses to another ear, of means for holding said member in operative relation to said receiver ear piece comprising a spring provided with fingers engaging said member and said ear piece.

6. The combination with a telephone receiver and means for rendering its impulses audible to both ears of an operator, comprising a plurality of ear pieces, of means whereby one of the ear pieces is automatically cut out when not in use.

7. The combination with a telephone receiver adapted to produce an effect upon one ear of an operator and means connected therewith and adapted to transmit said effect to another ear of means whereby the

loss of said transmission is automatically avoided when the same is not utilized.

8. A plurality of ear pieces operatively connected with each other combined with means whereby a telephone receiver placed in operative relation to one ear piece transmits sound also to the other ear piece, and means whereby said transmission is automatically arrested when said latter ear piece

10 is not in use.

9. The combination with a receiver having an ear piece of a plurality of ear pieces operatively connected with each other in such manner that when one of the ear pieces 15 is placed in operative relation to the ear piece of the receiver sound may be emitted from the plurality of ear pieces, and means

whereby one of the ear pieces may be automatically cut out.

10. The combination with a telephone receiver, an ear piece adapted to be placed against the ear of an operator, another ear piece adapted to be placed against another ear of an operator and means operatively connecting said last named ear piece with 20 said receiver comprising a sound tube, of means whereby the connection of said sound tube is automatically cut off depending upon the position of the ear piece.

JOHN L. CREVELING.
